(57) **CLAIM**

The ornamental design for a display screen with a graphical user interface, as shown and described.

DESCRIPTION

The sole FIGURE is a front view of a display screen with a graphical user interface.

The broken lines showing a mobile device illustrate environmental structure and form no part of the claimed design. All other broken lines in the drawings showing the display screen and elements of the graphical user interface illustrate portions of the article and that form no part of the claimed design.
